UNITED STATES PATENT OFFICE.

RICHARD C. NEPTUNE, OF INDIANAPOLIS, INDIANA.

ROOF.

Application filed January 12, 1926. Serial No. 80,791.

My invention relates to composition roofing, of the type known as roll roofing, more particularly, and has as its essential object the provision of a roof laid from flexible rolls, 5 in which there are nailed lap joints, with complete coverage for all nails.

In detail it is my object to provide roll roofing with a surface finish except for a space at both edges, known as a selvedge, in 10 the roofing art. At the selvedge the finish is omitted, so that by lapping the selvedges, there will be left a depression between each strip as applied. This strip is then covered with a pasted down narrow strip, which not 15 being required to possess great strength, can be made thin enough to leave a level surface to the whole roof, if this be desired. Also the narrow bands can be of different color or nature.

20. There is no added factor of applying a sealing compound of asphaltic nature over the joints between strips, as this is customarily done anyhow, and there is the very decided advantage in that the rolls are reversible, so that when cut off diagonally at any 25 angle, at a hip in the roof, the same strip can be turned 180 degrees, and the same angle will be presented for starting the next strip. As is evident, this saves waste in laying roofs, 30 and in many cases this saving is very considerable.

I accomplish the advantages described together with others which will be noted, by that certain construction and arrangement 35 of parts to be hereinafter more specifically pointed out and claimed.

In the drawing:—

Figure 1 is a plan view of a piece of flexible roofing.

40. Figure 2 is a like view of the sealing band.

Figure 3 is a section taken across Figure 1, on line 2, 2.

Figure 4 is a section taken across Figure 2, on line 4, 4.

45. Figure 5 is an enlarged section of the covered lap joint.

Figure 6 is a section on a larger scale, showing the method of laying the strips.

The roll roofing which will ordinarily be 50 used by me, will be normally formed of a body of felt 1, having a mastic coating, the surface of which is covered with mineral granules as indicated at 2. The felt body is left free of mastic and granular surfacing at 55 3, along each lateral edge, thereby forming a double selvedge for each strip.

The sealing strip is formed preferably of a lighter gauge felt 4, with a surfacing 5, which is similar to the surfacing 3, but not so thick. The color of the mineral surfacing 60 may be the same as the main roofing strips, or it may be different, and the width of the sealing strip will preferably be the same as the lap joints formed in applying the selvedge of one strip over the selvedge of the adjoining strip. It may, however, be wider than the joint, for special effects.

The best way of laying roll roofing is vertically of the roof deck. As indicated the strips are laid from left to right or right to 70 left, with the selvedges 3 overlapping. The nails 5^a are driven through the lapped selvedges into the roof deck.

Then an adherent substance, preferably asphaltic in nature, is applied to cover the 75 lapped selvedges, and the small strip is laid with the surfacing 5 on the outside, so as to cover the lapped selvedges, and adhere thereto.

When a hip is reached by a strip it is cut 80 off, at the angle suitable to make a fit, and the roll then turned around and the next course laid, by applying the angularly cut off edge to the hip, where it will fit properly.

The thickness of the sealing strip is not es- 85 sential, although normally it will be of a thin enough gauge, to do no more than fill the joint made by the lapped selvedges.

Various modifications will occur to those skilled in the art, by means of which roofs can 90 be built, like those illustrated by me, without any exposed nail heads, with special color banded effects, or without any substantial showing of the presence of the sealing strips.

Having thus described my invention, what 95 I claim as new and desire to secure by Letters Patent, is:—

1. In a roof, the combination of strips having a felt body, and a granular surfacing, said surfacing being removed at the edges to 100 form selvedges, said strips laid so as to overlap at the selvedge and nailed to the roof deck through the selvedges, and sealing strips secured over the selvedges, said strips also being formed of a felt body with granular surfacing thereon but having an overall thickness sub- 105 stantially the same as the thickness of the granular surfacing on the felt bodies.

2. In a roof, the combination of strips having a felt body, and a granular surfacing, 110 said surfacing being removed at the edges to form selvedges, said strips laid so as to

overlap at the selvedges and nailed to the roof deck through the selvedges, and sealing strips secured over the selvedges, said strips also being formed of a felt body with granular surfacing thereon but having an over all thickness substantially the same as the thickness of the granular surfacing on the felt bodies, said sealing strips being secured over and covering the lapped joints, and being 10 equal to the width of the joint so formed by said selvedges.

3. In a roof, the combination of strips having a felt body, and a granular surfacing, said surfacing being removed at the edges to 15 form selvedges, said strips laid so as to overlap at the selvedges and nailed to the roof deck through the selvedges, and sealing strips secured over the selvedges, said strips also being formed of a felt body with granular

surfacing thereon but having an over all 20 thickness substantially the same as the thickness of the granular surfacing on the felt bodies, said sealing strips being of a width at least to cover the selvedge lapped joints, and secured in place by an adhesive layer 25 applied over the joints.

4. In a roof, the combination of shingle strips having a granular surfaced outer face, and having selvedges of reduced thickness, said strips laid so as to overlap at the selvedges, and means securing the selvedges of said strips to the roof deck, and joint strips to cover the selvedges also having a granular outer surface, said strips being narrower than the first mentioned strips and of reduced 30 thickness so as to form a uniform plane surface of the roof.

RICHARD C. NEPTUNE.
